BOX

Russell C. Folk, Reading, Pa.

Application December 9, 1955, Serial No. 39,256

Term of patent 14 years

(Cl. D58—12)

Fig. 1 is an exploded perspective view of a box showing my new design; and

Fig. 2 is a perspective view thereof in closed position and diametrically opposite to that shown in Fig. 1.

The box is shaded to represent contrast in color.

I claim:

The ornamental design for a box, as shown and described.
